UNITED STATES PATENT OFFICE.

RAYMOND A. LEMP, OF SYRACUSE, NEW YORK.

LAVATORY DRYING DEVICE.

Application filed November 28, 1927. Serial No. 236,240.

This invention relates to an air heating device adapted to be installed in lavatories, tonsorial parlors, beauty shops and analogous places for drying the hands, face and hair 5 after laving or other ablutions.

I am aware that various devices have heretofore been proposed for heating and propelling currents of air for similar purposes in which the moistened hands and faces are 10 usually positioned directly in the path of the moving current of heated air with the face some distance above the hands so that both may be drying at about the same time under which conditions it frequently happens that 15 the moisture liberated from the hands by the current of air will be more or less sprayed or spattered upon the collar and other garments of the user due to the impact of the heated air against the hands which is particularly true in machines using motor driven 20 fans as the air-propelling medium.

The main object of the present invention is to avoid this objectionable result by directing a portion of the heated air current 25 in more or less opposition to the upflow of the main current and thereby to break the force of upflow of the main current which incidentally prevents the carrying of the moisture spray upwardly from the hands when 30 the latter are positioned in the path of movement of the main current.

Another object is to utilize this branch or bypass current in connection with the main current for drying a greater area of the hands 35 at one and the same time than would be possible with a single current, thereby expediting the drying operation.

A further object is to extend a portion of the device over and some distance above the 40 inlet for the main current to form a baffle hood having an opening therethrough for directing the main current upwardly to be used in drying the face at the same time that the hands are interposed between the hood and inlet 45 for drying purposes.

Another object is to provide a simple and comparatively inexpensive device of this character which may be made and sold as a unit or may be attached to the pressure side 50 of a motor driven fan or equivalent air-circulating medium.

Other objects and uses relating to specific parts of the device will be brought out in the following description.

In the drawings:—

Figure 1 is a top plan of air-heating device embodying the various features of my invention.

Figure 2 is a vertical sectional view of the same device taken in the plane of line 2—2, 60 Figure 1.

Figure 3 is a horizontal sectional view taken in the plane of line 3—3, Figure 2.

Figure 4 is a vertical sectional view taken in the plane of line 4—4, Figure 1.

As illustrated, this device comprises a tubular base —1—, a bracket —2— extending upwardly from the base —1— mainly at one side of the axis of said base and preferably curved longitudinally so that its upper 70 end may extend over and some distance above the base —1— to form a baffle hood —3— and an intervening open space —4— between the base and hood of sufficient height and depth from front to rear to receive the hands of the 75 user.

The tubular base —1— is shown as cylindrical and relatively short axially but obviously may be made of any cross sectional form for connection with the pressure side 80 of a fan case, if desired. The intent, however, is to enable the device to be made and sold as a unit to be used in connection with or separate from a motor driven fan, not shown.

When used separately the device may be 85 attached by any suitable fastening means to a support capable of holding it in an upright position and in such manner as to permit free flow of the air through the base —1— and hood —3— and across the intervening space 90 —4— which is left available for reception of the hands with ample space above the hood to permit the face of the user to be placed directly over the opening in the hood.

Under these conditions the base —1— will 95 be provided with an internal heater —5— preferably of the electric type having means such as a cable —a— and plug —b— for connection with a lamp socket for supplying current to the heater.

This heater extends entirely across the interior area of the base —1— and is preferably made in grille form to allow free flow of air from the bottom upwardly therethrough for heating the air as it passes from the under- 100 side of the base upwardly.

The bracket —2— is concavo-convex in cross section and also longitudinally with its

convex side outermost and its concave side facing the opening —4— between the base —1— and hood —3—, said bracket being provided with a lengthwise partition —6— extending from the central portion of the upper end of the base —1— to a point between the horizontal center of the opening —4— and back of the hood and connecting the opposite walls of the concave side of the bracket in spaced relation to the rear wall thereof to form a lengthwise passage —7—.

10 The mouth of the passages —7— is equal to approximately half the cross sectional area of the tubular base —1— while the upper end 15 of the other half of the base is open at the top to allow the heated air to pass from the bottom upwardly therethrough and at the same time allowing a portion of the heated air to pass upwardly through the passage —7—.

20 The upper portion of the bracket —2— is provided with an inwardly projecting baffle flange —8— in longitudinally spaced relation to the upper end of the partition —6— to form an outlet —9— which is inclined downwardly and inwardly for deflecting the heated air from the upper end of the passage —7— downwardly and inwardly to meet the upwardly flowing current of air through the main passage as —10— some distance below 25 the hood —3— or rather between said hood and the base —1—.

For this latter purpose the flange —8— and a similar flange —8'— on the upper end 30 of the partition —6— are deflected downwardly and inwardly from the outer wall and from the partition respectively.

35 The hood —3— extends forwardly over and beyond the upper end of the base section —1— in an approximately horizontal plane, 40 but is concavo-convex in cross section, both longitudinally and transversely and is provided at its forward end with a downwardly and forwardly extending flange —3'— to assist in directing the upflowing current of 45 heated air from the base section —1— through an opening —11— in the top of the hood.

If desired a screen —12— may be placed over and upon or within the upper end of the main passage —10— to prevent lodging of 50 foreign matter upon the underlying heater —5—. The heater —5— may be of any well-known or desired construction such, for example, as a resistance wire —13— mounted upon and within an insulating ring —14— 55 which is removably held in operative position within the base —1— by clamping screws —15— or equivalent fastening means.

Operation.

60 Whether this device is used as a separate unit or in connection with a motor driven fan, the cold air entering the bottom of the base section —1— will be heated and the heated air will rise through the main passage —10—

and by-pass —7— to mingle in the opening 65 —4— by reason of the discharge of the bypassed heated air through the outlet —9— and into said opening in such manner as to intersect the upwardly moving current of air through the passage —10—.

70 The purpose of the downwardly and inwardly deflected passage —9— is to break the force of the upwardly moving current of heated air passing through the main passage —10— so that when the moistened hands of 75 the user are placed in the opening —4— they will be subjected to drying influence of the current from below through the main passage —10— and also by the heated current escaping from the by-pass —7— through the outlet —9— which, by reason of its downward and inward deflection, tends to dry the upper portions of the hands and to deflect downwardly any loose moisture which may be liberated from the hands by the upwardly moving current of air from the main passage —10—.

80 In other words, the by-passed heated current of air escaping through the discharge nozzle —9— serves the double purpose of increasing the drying effect of the air upon the hands and also preventing the loose moisture on the hands from being forced upwardly through the outlet —11— of the main heated current.

85 While the hands are being dried in the opening —4— by the main current and also by the by-passed current of heated air portions of said heated air will naturally pass around the hands and upwardly through the outlet —11— over which the face of the user 90 may be held for drying the face and hair, if desired.

95 Or, the hands may be dried separately in the opening —4— and the face dried separately over the opening —11—, it being understood that the hoods —3— by reason of its peculiar concavo-convex shaft tends to direct the heated air from the opening —4— upwardly through the outlet —11—.

100 The unitary frame having the various elements as described is particularly simple, practicable and highly efficient as a drying medium for the face and hands, but obviously may be modified materially in its detail 105 construction without departing from the spirit of this invention.

110 A damper —16— is pivoted to the side walls of the chamber —7— adjacent the outer face of partition —6— between the inlets and outlets of said chamber or by-pass —7— to swing from a normal open position adjacent the partition across the chamber, said damper being mounted upon a rock shaft —17— which extends through one of the side walls of the chamber —7— and is provided at its outer end with a handle —18— by which the damper 115 may be closed at will.

The damper —16— is adapted to open by its own weight aided by the weight of the handle —18—.

It will be observed, however, that the free edge of the damper —16— normally lies closely adjacent the partition —16— and, therefore, is not affected by the flow of air through the chamber —7— until it is partially closed by the user and when left in its open position permits the portions of the heated air to flow through the chamber —7— and through the outlet —9— to mingle with the main current of air flowing upwardly from the tubular base —1— through the opening —11— in the hood —3—.

If desired, the deflecting flange —8— may be extended upwardly at —8''— to the top of the rear side or wall of the opening —11— to assist in directing the currents of air upwardly through said opening.

When drying the hands they are interposed in the path of the main air current and also in the path of the downwardly and inwardly deflected by-passed air current thereby retarding the direct upflow of the main current through the hood and causing it to spread out over a greater area of the hands while the by-passed current is directed against the remaining portions of the hands, thus completing the drying of the hands in an extremely short space of time and greatly reducing the amount of current necessary for the drying operations.

On the other hand, when it is desired to dry the face, exclusive of the hands, it is most expeditiously accomplished by closing the damper in the by-pass which allows all of the heated air to pass upwardly through the hood and directly against the overhanging face of the user.

What I claim is:—

1. In an air-heating device of the character described, an upright tubular member having a main air outlet at the top and a branch passage leading upwardly from the interior thereof at one side of the main passage and provided with an inwardly and downwardly inclined outlet in a plane above the tubular base for deflecting heated air across the upflow current of heated air from the main passage, and means for heating the air in transit to the main outlet and to the branch passage.

2. An air-heating device of the character described comprising an upright tubular base permitting the flow of air therethrough, a hood supported directly over the upper end of the tubular base in spaced relation thereto to permit the placing of the hands between the base and hood for drying purposes and provided with a vertical opening therethrough, a bracket connecting the base to the

hood and provided with an air passage having its lower end communicating with the interior of the base and its upper end provided with an outlet discharging into the space between the base and hood, and means for heating the air in transit through the tubular base.

3. In an air drier of the character described, a base having a main vertical air passage at one side of its axis and an upwardly extending tubular bracket at the opposite side of its axis having its lower end communicating with the interior of the base and its upper end provided with an outlet discharging downwardly and inwardly toward the produced axis of the base, and means for heating the air in transit through said base and tubular bracket, and a damper within the tubular bracket for regulating the flow of heated air therethrough.

4. In an air-heating device, an upright base having a main air passage therethrough, a hood overhanging the base in vertically spaced relation thereto and provided with an air-opening therethrough in vertical alignment with the main passage of the base, a bracket connecting the base and hood and provided with a branch passage communicating at its lower end with the interior of the base and its upper end discharging into the intervening space between the base and hood, a damper in the branch passage, and means for heating the air in transit through the main passage and branch passage.

5. An air-heating device of the character described comprising a tubular base having an upwardly extending bracket mainly at one side of the axis of the base, a hood supported upon the upper end of the bracket directly over and in spaced relation to the base, said base and hood being provided with vertically aligned air passages, the bracket being provided with an air passage having its lower end communicating with the interior of the base and its upper end provided with an outlet discharging into the intervening space between the base and hood, and means within the base for heating the air in transit therethrough.

6. In an air-heating device of the character described a frame having a main air passage and a branch air passage at one side of the main passage, the branch passage being provided with a discharge opening in a plane above the upper end of the main passage, a damper controlling the branch passage, and means for heating the air in transit through said passage.

In witness whereof I have hereunto set my hand this 23d day of November, 1927.

RAYMOND A. LEMP.
